Tulsa, Okla., a corporation of Delaware

Application January 9, 1937, Serial No. 119,751

2 Claims. (Cl. 196—18)

This invention relates to processes of separating wax from oils. Prior to this invention, propane and other normally gaseous solvents have been employed as selective dewaxing solvents, the

operations being carried out under pressure which is gradually reduced to permit evaporation of some of the solvent, and thereby chill the remaining solution to the dewaxing temperature. An advantage gained by the old use of such normally gaseous dewaxing solvents lies in the refrigeration which is readily obtained by evaporating a predetermined portion of the solvent. However, disadvantages appear in the requirement for relatively high pressures throughout the system, including the filters, or the like, where the precipitated wax is separated from the chilled solution. In using propane a further disadvantage lies in the extremely low dewaxing temperature, which is usually about -40° F., requiring very expensive equipment to withstand the extraordinary temperature changes, especially when subjected to the operating pressures. The cost of chilling the solution to a temperature far below 0° F. is another expensive factor in the use of propane and the like.

Normally liquid dewaxing solvents provide the advantage of operating under approximately atmospheric pressure, in more simple and less expensive equipment, as well as the advantage of dewaxing at much higher temperatures, for example about 0° F. However, the old methods of using these normally liquid dewaxing solvents lack the advantage of evaporation in the solution to provide the dewaxing temperature.

An object of the present invention is to obtain advantages of both of the old dewaxing processes, without incurring the outstanding disadvantages of either type. More specifically stated, an object is to so use a normally gaseous refrigerant that it is not necessary to employ all of the high pressure conditions, nor the very expensive equipment required for extremely low temperatures; at the same time avoiding the excessive operating expense involved in producing such extreme temperatures. Otherwise stated, an object is to employ a normally liquid dewaxing solvent, so as to obtain the advantage of dewaxing at comparatively high temperatures in a relatively simple and inexpensive system, while obtaining the advantage of evaporation in the solution to provide the desired low temperature.

In one form of the invention, we produce a solution of wax-containing oil and normally liquid dewaxing solvent in the proportions required for precipitation of the wax to be removed.

To this dewaxing solution we add a refrigerant which is mixed with the solution to perform its function as a cooling agent, and then removed before the wax is separated from the solution. The normally gaseous refrigerant may be propane, methyl chloride, dimethyl ether, or any other normally gaseous material adapted to be introduced in a liquid state and removed by evaporation which results in the chilling.

The normally liquid dewaxing solvent may be employed in quantities sufficient for all of the selective action desired in the precipitation of the wax, and in this event, the dewaxing may be carried out at relatively high temperatures. The normally gaseous material may be employed for refrigeration alone, so as to avoid objections to the presence of such material during the operation of removing the wax. For example, in using propane as a refrigerant, we endeavored to remove all of the propane from the chilled solution, as the presence of propane during the operation of removing the wax would require a lower temperature for the precipitation of the wax. However, in commercial practice, it is not necessary to remove all of the propane, or other refrigerant, as a small quantity of this material will not substantially interfere with the operation. Therefore, it is to be understood that when we refer to evaporation of the refrigerant, we mean a substantial evaporation required for the cooling, and this does not require a complete removal of the refrigerant from the solution.

Another object is to produce a continuous dewaxing system wherein the refrigerant is introduced into and removed from the dewaxing solution, without requiring the use of very expensive and troublesome batch chillers, which are ordinarily employed in commercial systems using normally gaseous dewaxing solvents. In one form of the invention, a normally gaseous refrigerant is evaporated in the dewaxing solution while a stream of the mixture is flowing through an elongated passageway, thereby gradually chilling a continuous stream of the solution as it progresses toward the dewaxing station. Or, if desired, the continuous stream of dewaxing solution may be chilled by introducing a cold stream of refrigerant into the flowing solution while it is advancing toward the dewaxing station. The cooperative effect of these two different features can be conveniently obtained by introducing a stream of chilled refrigerant into the continuous stream of dewaxing solution, thereby cooling the stream of solution, and there-

after evaporating the refrigerant in the flowing stream to continue the chilling operation.

Another object is to produce a dewaxing process wherein the solution to be dewaxed can be very quickly chilled, with the result of precipitating wax in a form that can be very readily removed by filtration.

With the foregoing and other objects in view, the invention comprises the novel process hereinafter more specifically described and shown in the accompanying drawing, which illustrates one form of the invention. However, it is to be understood that the invention comprehends changes, variations and modifications within the scope of the claims hereunto appended.

The drawing is a diagrammatical view of a dewaxing system embodying features of this invention.

In the system illustrated by this drawing, the oil stock to be dewaxed flows from a tank 1 through a pipe 2 leading to a heater or cooler 3 where the oil stock may be heated or cooled to the desired temperature. The stream of oil then flows through a pipe 4 to a mixer 5. A normally liquid dewaxing solvent flows from a supply tank 6 through a heater or cooler 7 and thence to the pipe 4 where it enters into the stream of oil. The constituents of the two streams, at a temperature desired to form the solution, are mixed in the mixer 5 and conducted through a heat exchanger 8 to a pipe 9 leading to a pump 10 which forces the solution through a pipe 11 to a mixer 12, where the solution is mixed with a refrigerant.

A liquefied normally gaseous refrigerant flows from a supply tank 13 through a pipe 14 to a heat exchanger 15 where it is cooled, and then conducted through a pipe 16 to a chamber 17. The liquefied refrigerant is under a pressure which may be reduced in the chamber 17 to evaporate a portion of the liquid, thereby cooling the remaining liquid. A stream of this cooled refrigerant is discharged from the chamber 17 through a pipe 18 to a pump 19 which forces the cold liquid into the mixer 12, where the cold stream unites with the stream of solution from the pipe 11. The solution to be dewaxed is very suddenly cooled by the cold stream of refrigerant in the mixer 12.

The two streams are constantly transmitted into the mixer 12, and the resultant cooled stream of solution and refrigerant, together with precipitated wax, is preferably conducted through a pipe 20 to an elongated chilling passageway formed by a coil of pipe 21. It is to be understood that the mixture enters this elongated passageway under a pressure high enough to retain the normally gaseous refrigerant in a liquid condition, but as the mixture progresses through said passageway the pressure is gradually reduced, so as to gradually evaporate the refrigerant, and thereby gradually cool the material to be dewaxed. This gradual reduction in pressure may be due to high pressure at the inlet of the elongated pipe 21 compared to low pressure at the discharge end of the pipe, and if desired, various mechanical expedients may be employed to aid in reducing the pressure. The desired result can be obtained by using pipes of uniform diameter in the chilling coil 21, or a flaring condition can be obtained by gradually increasing the diameter from a relatively small dimension at the inlet of the coil 21 to a larger diameter at the outlet. The discharge end of the coil 21 herein shown is connected by means of a pipe 22 to a chamber 23 which may be under about atmospheric pressure, or under a partial vacuum.

Approximately all of the refrigerant may be evaporated in the stream of solution flowing through the elongated chilling passageway at 21, and the resultant gas may be separated from the chilled solution in any suitable manner. For example, this gas may be released in the chamber 23 under about atmospheric pressure, or lower, and conducted through a pipe 24 to a compressor 25 which discharges through a pipe 26 to a cooler 27. The gaseous refrigerant is thus condensed and returned in a liquid state through pipe 28 leading from the cooler 27 to the supply tank 13.

It will be observed that the refrigerant may be forced into and then removed from a constant stream of the solution to be dewaxed. In other words, the normally gaseous refrigerant may be utilized solely for refrigerating, while normally liquid dewaxing solvent performs the selective action desired for dewaxing. In this event, all of the wax can be precipitated at relatively high temperatures, for example, 0° F. or higher.

After being chilled by the refrigerant and then separated therefrom, the mixture to be dewaxed may be transmitted from the chamber 23, through a pipe 29 to a continuous rotary filter 30, where the wax is constantly removed through a conductor 31, while the dewaxed solution is constantly discharged through a pipe 32 leading to a tank 33. This cool solution may be transmitted through a pipe 34 to the heat exchanger 15, thence through a pipe 35 to the heat exchanger 8, and pipe 36 leading to a solvent recovery system 37. At this point, the normally liquid solvent may be distilled from the dewaxed oil and returned through a pipe 38 to the supply tank 6.

In carrying out the process, a substantial advantage will usually be obtained by evaporating the refrigerant in the mixed stream flowing through the elongated passageway formed by the chiller 21. However, if desired, the mixture of refrigerant and dewaxing solution may be transmitted from the pipe 20 through a by-pass 39 leading directly into the low pressure chamber 23, where the refrigerant may be gradually evaporated in the usual manner to chill the wax-containing solution.

It is to be understood that the refrigerant may be united with the solution at any desired point and at any desired temperature. However, an advantage is gained by the extremely rapid chilling obtainable from this process. The chilled stream of refrigerant at an extremely low temperature, for example, -40° F. or considerably lower, may be forced into the stream of dewaxing solution, so as to quickly chill the solution at a rate in excess of 20° F. per minute (1200° F. per hour), which results in sudden precipitation of wax. We have found that this result can be very economically obtained without causing any difficulty in filtering the precipitated wax from the solution. The extremely low temperature of the refrigerant can be conveniently obtained by evaporating a portion of the normally gaseous liquid in the chamber 17, the gas being discharged through a pipe 40 to a compressor 41 which forces the compressed refrigerant into the return line 26, while the stream of chilled liquid is constantly discharged through the pipe 18 to the mixer 12.

The invention is not limited to the use of any particular refrigerant, examples of which are found in propane, methyl chloride, dimethyl ether, and other normally gaseous liquids. However, it is usually convenient to use mixtures of normally gaseous hydrocarbons, such as commer-

cial propane. Any suitable normally liquid dewaxing solvent may be employed. Specific examples of such dewaxing solvents include butyl acetate, amyl acetate, isopropyl acetate, and 5 blends of these solvents, or a blend of one of said solvents and dichlorethyl ether. Other examples appear in mixtures of acetone and benzol, and normally liquid solvents of this type. However, the invention is not limited to the use of 10 any of the dewaxing solvents herein specified.

One volume of the oil to be dewaxed may be dissolved in about two to three volumes of the normally liquid dewaxing solvent, using a quantity of this solvent sufficient for precipitation of 15 all of the wax to be removed in the process. Numerous liquid solvents of this kind can be employed to obtain a pour point within 20° F. of the dewaxing temperature, and in using a number of these normally liquid solvents, the 20 ultimate pour point will be equal to or very substantially below the dewaxing temperature, which is quite different from the extremely low temperatures required in using propane as a selective dewaxing solvent. The oil and normally 25 liquid dewaxing solvent may be heated at 3 and 7, respectively, to a temperature that will result in complete solution of the oil and wax in the solvent, and then cooled to precipitate the wax. A preliminary cooling to a temperature slightly 30 above the temperature at which the wax begins to precipitate can be conveniently obtained in the heat exchanger 8. A continuous stream of this dewaxing solution is mixed with a continuous stream of cold refrigerant, such as chilled propane, in the mixer 12 at a temperature of 0° F. to 35 -44° F. or lower. This mixing of the continuous streams suddenly chills the dewaxing solution 20° or more. The substantially instantaneous chilling may be serve enough to precipitate 40 most of the wax. The propane is then evaporated on the elongated passageway formed by the chilling coil 21 or in the chamber 23 to chill the solution to the desired dewaxing temperature. The quantity of propane employed may be just sufficient 45 to produce the predetermined dewaxing temperature, and in this event, approximately all of the propane will be evaporated from the dewaxing solution. The precipitation of wax will then be determined by the nature of the normally 50 liquid dewaxing solvent, and the function of this solvent as a wax-precipitant will not be impaired by the presence of a substantial quantity of the refrigerant. We thus obtain the 55 advantages of propane, or other normally gaseous material, as a refrigerant, without the disadvantages of chilling to extremely low temperatures.

As a very specific example we will refer to the dewaxing of a Mid-Continent lubricating oil distillate having an A. P. I. gravity of 23.8, a Saybolt Universal viscosity of 74 at 210° F. and a pour point of 110° F., which we dewaxed at 0° F. and obtained a lubricating oil having a pour point of -5° F. As a dewaxing solvent we employed a blend of 80 percent isopropyl acetate and 20 percent amyl acetate. One volume of the wax-containing distillate may be mixed with 3 volumes of said dewaxing solvent at a temperature of 120° F. at the mixer 5, the resultant solution being cooled to 95° F. in the heat exchanger 8. A continuous stream of this solution may be mixed 60 with one and one-half volumes of cold propane, at a temperature of -40° F. or lower, in the mixer 12. In one form of the invention, the wax-containing solution is thus suddenly chilled to about 70 40° F. to 60° F., and the resultant mixed stream 75

enters the elongated chilling coil 21 under a pressure of about 40 pounds per square inch. The pressure is gradually reduced as the mixed stream progresses through the elongated passageway formed by said coil 21, and the mixture 5 is discharged from the passageway to the chamber 23 under atmospheric pressure or lower. In the example given, the mixture was chilled to 0° F. and dewaxed to produce a lubricating oil having a pour point of -5° F.

In another example, a blended lubricating oil stock consisting of residuum 40 percent, heavy distillate 30 percent and medium distillate 30 percent, having a Saybolt Universal viscosity of 110 at 210° F. and a pour point of 105° F., was 15 dewaxed at 10° F. above 0° F. to obtain a bright stock having a pour point 5° F. lower than the dewaxing temperature.

The sudden chilling at a rate in excess of 20° F. per minute (1200° F. per hour), for example, 20 about 350° F. per minute, does not result in any difficulty during the step of removing the wax from the solution. Actual tests have shown that the suddenly chilled solution can be very rapidly filtered, so as to obtain the important advantage 25 of very rapid chilling, as well as rapid and efficient filtration.

This extremely sudden chilling may be practically instantaneous. For example, a drop of approximately 40° F. can be obtained in about 30 5 to 10 seconds, which would be a rate of 240° F. to 480° F. per minute, the equivalent of about 14,400° F. to about 28,800° F. per hour. The average chilling rate for the extremely sudden chilling combined with gradual chilling in the 35 coil 21 may be in excess of 1200° F. per hour.

The cold stream of liquefied normally gaseous refrigerant, which enters the stream of solution at the mixer 12, could be at a temperature so low that further chilling is unnecessary. However, it is most convenient to evaporate the refrigerant as the mixed stream advances through an elongated passageway, thereby reducing the temperature to the desired degree and also removing the refrigerant from the mixture to be 40 dewaxed. Or, instead of using the elongated passageway in the chiller 21, and even without previous chilling of the normally gaseous liquefied refrigerant, the mixture could be transmitted under pressure through the by-pass 39, and 45 thence into the chamber 23, where the pressure may be released to evaporate the refrigerant from the mixture to be dewaxed. In this event, the chamber 23 could serve as an ordinary batch chiller, or evaporator. In either case, the normally 50 gaseous refrigerant could be introduced into and removed from the normally liquid dewaxing solution, so as to permit separation of the wax in a simple apparatus, under about atmospheric pressure. By eliminating the normally 55 gaseous refrigerant after it has chilled the normally liquid solution, one can then dispense with high pressure in the subsequent operations, and also overcome any undesirable effect that the refrigerant may have upon the pour point or 60 other properties of the dewaxed product.

It will now be understood that we have disclosed a process wherein a normally liquid solvent and a normally gaseous refrigerant may be employed to obtain the combined advantages of 65 these two different types of materials, without incurring the outstanding disadvantages heretofore involved in using either of said materials. Furthermore, we have specifically shown how to accomplish this result in a simple continuous sys- 70 75

tem, where streams of the several materials are constantly flowing through the system, while maintaining a constant condition at any given point in the system, and without requiring the use of expensive and troublesome batch chambers, or the like, where there is a frequent change in either pressure, temperature, or volume of material. However, it is to be understood that the invention is not limited to specific combinations herein disclosed, except as specified in the claims which are intended to cover equivalents and modifications of the several features herein specifically described.

We claim:

1. In the art of separating wax from lubricating oil stocks, the method which comprises mixing the wax-containing oil with a normally liquid dewaxing solvent at a temperature high enough to dissolve the wax and oil in said dewaxing solvent, continuously introducing a cold stream of liquefied normally gaseous refrigerant into a stream of said solution to suddenly chill the solution and quickly precipitate wax therein, transmitting the mixture in the form of a continuous stream through an elongated passageway and at the same time gradually evaporating approximately all of the refrigerant in the flowing mixture to gradually continue the chilling and precipitation of wax, separating the refrigerant

from the chilled mixture, and thereafter removing the wax from the chilled solution of oil and normally liquid dewaxing solvent.

2. In the art of separating wax from lubricating oil stocks, the method which comprises mixing the wax-containing oil with a normally liquid dewaxing solvent at a temperature high enough to dissolve the wax and oil in said dewaxing solvent, the ratio of said oil and normally liquid dewaxing solvent being sufficient for precipitation of the wax to be removed in the process, cooling a continuous stream of the solution of wax-containing oil and normally liquid dewaxing solvent, continuously introducing a cold stream of liquefied propane into said stream of solution to suddenly chill the solution and quickly precipitate wax therein, transmitting the mixture in the form of a continuous stream through an elongated passageway and at the same time gradually evaporating approximately all of the propane in the flowing mixture to gradually continue the chilling and precipitation of wax, separating the propane from the chilled mixture, and thereafter removing the wax from the chilled solution of oil and normally liquid dewaxing solvent.
